APPARATUS FOR EXPRESSING OIL FROM
OIL BEARING MATERIALS

Raymond Tuttle Anderson, Berea, Ohio, assignor
to The V. D. Anderson Company, Cleveland,
Ohio, a corporation of Ohio

Original application August 1, 1936, Serial No.
93,907. Divided and this application August 14,
1940, Serial No. 352,628

4 Claims. (CL. 100—48)

This invention pertains to an improved apparatus for expressing oil from proteinaceous materials containing the same. Although the invention is of general application in expressing oil from proteinaceous oil bearing materials, it will be described, by way of example, as applied more particularly to the treatment of soya beans.

The main object of the invention is directed to apparatus for producing a high grade, light-colored oil from such proteinaceous materials, by use of mechanical presses.

In a broad sense, the invention comprises a press in which the oil bearing material is subjected to high compression to express the oil. Working in conjunction with said press is means for subjecting the body of the press to the action of a cooling medium, such as oil, to lower the temperature of the press and maintain it at such a temperature that oil flowing from the material under treatment in the press will not be discolored. The problem presents the difficulty of preventing contamination of the expressed oil, hence the desirability of utilizing the expressed oil as the cooling agent for the press.

In the utilization of a continuously operating mechanical press, wherein the material is subjected to high pressure increasing as the material reaches the discharge of the press, high temperatures ordinarily prevail and the oil is discolored or darkened to such an extent as to render it unsuitable for certain uses. For instance, prime crude soya bean oil must be under 130 yellow and 36 red, while the trade demands that it be as close to 120 yellow and 24 red as is possible. These colors are determined by the Lovibond tintometer, which is a colorimeter for comparing the color of a liquid with the standard coloring solution on a series of tinted slides.

I have found that by utilizing a press of the type shown in Letters Patent No. 1,773,771, issued to me under date of August 26, 1930, or presses of the same general type, wherein a plurality of separated worms or screws are mounted upon a shaft within a press barrel having small openings in the wall thereof, combined with means for retarding the outflow of the compressed material from which the oil has been expressed, and subjecting the exterior of the press mechanism, or more specifically the barrel of the press as well as the feed chute leading into the intake of the shell or barrel, to the action of a cooling medium, I can produce oil of the desired quality.

Not only is a superior oil produced, but owing to the fact that the proteins of the material undergoing treatment do not become as fluid as

they do when the temperature is high, greater pressure may be exerted upon the mass without forcing such proteins outwardly through the passages or openings formed in the barrel for the outflow of oil.

The cake which is forced from the barrel past the choke has a lower oil content than would otherwise obtain, hence a greater yield of oil is produced through the lowering of the temperature of the press and of the material passing therethrough. The cake is also of lighter color than that which passes from a press which is uncooled.

Various media may be employed for bathing the exterior of the press structure, so long as they do not contaminate the expressed oil.

The present application is directed to the use of the preferred medium, namely oil and particularly oil which has been expressed from the material under treatment. It is usually necessary that it be cooled after it is expressed and prior to its being showered over the press structure. The oil lowers the temperature of the press and particularly the barrel bars, and holds the temperature of the mass being forced through the press at the desired value. What is perhaps more important is that the oil in flowing over the press barrel removes the foots, which are expelled from the barrel along with the oil. This keeps the exterior of the press barrel free of any accumulation, allowing the expressed oil to flow outwardly unimpeded and removing from the surface of the press barrel material which otherwise would have a tendency to insulate the structure against full action of the temperature lowering medium.

One embodiment of the apparatus capable of directing the cooling oil to and over the pressing mechanism is shown in the annexed drawing, wherein:

Figure 1 is a side elevation, with parts broken away, of so much of a press structure as is necessary to illustrate the means employed to shower or bathe the press barrel with oil;

Fig. 2 is a transverse sectional view on the line II—II of Figure 1; and

Fig. 3 is a diagrammatic view illustrating a series of presses utilizing a common cooling unit for oil which may be delivered to one or more of the presses.

Referring to the structure shown in Figures 1 and 2, 10 denotes the frame of a press such as shown in the patent above referred to. 11 designates the barrel, composed of a series of bars preferably arranged in circular series and held

in place with reference to each other and to the worms 12 (only one of which is shown) mounted upon a shaft 13. The bars 11 are held in position by heavy transversely extending spaced rib-like members 14, which are provided with semi-circular seats to receive the bars, the ribs being held together by longitudinally extending pressure bars 15 which, in turn, are rigidly secured together in oppositely disposed pairs by threaded bolt-like members 16. The lowermost pair of longitudinally extending bars 15 rests upon guideways or tracks 17 extending transversely of the base portion 10; only one of said tracks is shown (see Fig. 2).

The material is introduced into the barrel at the head end of the machine through a chute 18, which may be of any desired form (Fig. 1). The choke of the press may be of the type disclosed in Patent No. 1,752,054, dated March 25, 1930, or of any approved type which provides for adjustment.

The base of the frame 10 is formed into a trough 19 in the lower portion of which is mounted a worm 21 which may be rotated to remove foots which may settle from the oil, said foots being carried outwardly of the press structure for further treatment or return to the feed chute for introduction into the press along with the material being fed thereto. Located in the lower portion of the base 10 beneath the trough 19 are chambers 22, 23, through which a cooling medium is circulated. This medium has the effect of cooling the oil in trough 19 by heat exchange through the chamber walls. The expressed oil may flow from the trough through a lateral connection or conduit 24 and into the lower portion of a hollow leg 25 which extends upwardly to a point above the press structure proper. Within this leg is housed a bucket elevator 26 driven by any suitable means (not shown). The buckets at the upper end of the elevator discharge through an opening 27 onto a rifle board 28 which forms the lower element of a conduit extending from 27 downwardly and terminating in line with the longitudinal axis of the press structure proper. The various depressions or ripples 29 of the board 28 are so formed and contoured as to secure a substantially even distribution of the cooled oil onto and over the underlying press elements.

The cover plate 31 is disposed in spaced relation to the rifle board 28, said board and plate being supported by the proximate edges of the upper portion of two cover elements, 32 and 33, which are supported upon the frame 10 and extend upwardly to each side and over the upper portion of the press structure.

It will be readily appreciated that any suitable cooling medium may be employed to chill and lower the temperature of the oil in the trough 19, which cooled oil is picked up and carried to the rifle board and showered down upon the press barrel or shell. This has the effect of materially lowering the temperature of the shell and the associated elements and, consequently, lowers the temperature of the material being forced through the shell or barrel. The expressed oil not used in the cooling operation may be removed from trough 19 in any suitable manner.

Not only does the oil cool the press structure but it washes the foots from the exterior of the shell, keeping it clean and maintaining the passages between the shell bars free of accumulated foots, which otherwise would have a tendency to gum up and "char" thereon. Again, by reason

of the fact that the material in the barrel is cooled, the proteins are not as fluid as they would ordinarily be under usual operating temperatures. Hence, the mass as a whole which is being forced through the press is not so fluid and, consequently, the material will not pass the choke quite so readily and greater pressure may be exerted without raising the temperature beyond the limit where optimum conditions obtain both as to the quantity and color of the oil. Furthermore, by reason of the higher pressures permissible at the lower temperatures, the cake which is extruded from the press has a very low oil content and is light in color.

15 It will be appreciated that instead of the elevator as shown in Fig. 2 for carrying the oil to the rifle board, a pump may be employed.

In Fig. 3, a series of presses is indicated generally by 11^a, 11^b, 11^c, which are comparable to the press barrel 11 of Figs. 1 and 2. They are, of course, merely shown in a diagrammatic way, as are the other elements in this structure.

20 Located above and discharging upon each of the presses or barrels thereof is a rifle board, said boards being denoted by 28^a, 28^b, and 28^c, respectively. The oil which is gathered in the trough beneath each of the press barrels may be drawn off through lateral branches 34, 34^a, and 34^b, which branches are valved and open into a main 35 connected with a pump 36. The outlet of the pump is connected to a pipe 37 which passes into a cooler 38 that may be of any approved form having the usual connections for a refrigerant. The cooled or chilled oil passes from the cooler 38 into a main 39 provided with valved branches having nozzles 41, 41^a, and 41^b, which overlie and discharge upon the respective rifle boards.

25 As stated above, the showing in this figure is merely diagrammatic and a greater or less number of press elements may be present, or a single press may be utilized in conjunction with the pump and the cooler. The cooling action of the oil is the same as that which obtains with the construction first described.

30 To illustrate the advantages of the apparatus herein described, it may be pointed out that when operating a press of the type disclosed at high capacity on soya beans without cooling the press barrel, the expressed oil showed a color of 800 yellow and 340 red and the press was found to have a barrel temperature of 350° F. after removal of the foots. Also that at barrel bar temperatures of about 300° F. the material that is pressed out with the oil starts to darken and it is therefore essential that the barrel bars be kept at a temperature of approximately 300° F. or lower. The apparatus above described makes it possible to lower the temperature of the bars to 265° F. and maintain them at that temperature or lower. This lowering of the temperature insures the production of an oil having the requisite color index. The amount of cooling will obviously vary with the materials treated and also with the cooling medium used in the chambers 22 and 23 and in the cooler 38.

35 Where soya beans are being treated for the expulsion of oil, they will preferably be heated to approximately 270° F. prior to their entrance into the press.

40 While soya beans have been referred to specifically as the material being treated, it will be appreciated that the apparatus is capable of being utilized in connection with other proteinaceous oil bearing materials which it is desired to express.

This application is a division of my application Serial No. 93,907, filed August 1, 1936, Patent No. 2,216,658, such division having been made pursuant to requirement of the Patent Office.

What is claimed is:

1. In an apparatus for expressing oil from oil bearing materials, the combination of a mechanical press comprising a barrel having openings for the passage of oil therefrom, and means located within the barrel for compressing the material; a housing surrounding the barrel in spaced relation thereto; means for collecting oil expressed from the materials; means for cooling said oil; and means for showering at least a portion of such cooled oil onto the upper portion of the barrel, whereby the oil will flow over substantially the entire exterior surface of the barrel and the barrel temperature will be reduced.

2. In an apparatus for expressing oil from material containing the same, the combination of a continuously operating mechanical press including a press barrel; a trough located below said press and designed to receive the expressed oil; means associated with said trough for cooling the oil therein; means comprising a conduit extending from the trough to a point above the press barrel for conveying the oil to the upper portion of the press; a bucket elevator in said conduit; and means located adjacent the upper run of the bucket elevator for delivering the cooled oil from 30

3. In an apparatus of the character described, the combination of a continuously operating mechanical press designed to express oil from substances containing the same; a trough located beneath said press and into which the expressed oil is discharged and gathered; means for cooling said trough; a conduit extending outwardly from the trough and terminating in the lower end of a hollow leg; a bucket conveyer mounted in said leg; and a riffle board in communication with the leg at the upper end thereof, said riffle board delivering cooled oil onto the upper portion of the press, said oil serving to wash expressed solid matter from the press, as well as to cool the same.

4. In an apparatus for expressing oil from material containing the same, the combination of a continuously operating mechanical press including a press barrel with openings throughout substantially its entire surface for the escape of expressed oil; a trough located below said press and designed to receive the expressed oil; means for conveying and showering a portion at least of such expressed oil onto the upper portion of the press barrel, whence it flows over substantially the entire exterior surface of the barrel to remove solid matter therefrom; and means associated with the press for cooling all of the expressed oil that is showered over the barrel, whereby the barrel temperature will be reduced.

RAYMOND TUTTLE ANDERSON.
